ATTORNEY

UNITED STATES PATENT OFFICE

JOHN I. ROUTLEDGE, OF ETTRICK, ONTARIO, CANADA

GLAZIER'S POINT

Application filed August 14, 1931. Serial No. 557,062.

This invention is an improved glazier's point.

One object is to provide a glazier's point which may be quickly handled and located in position and inserted in the sash.

Another object is to provide a glazier's point which may be inserted with only the putty knife which is used for putting in the glass panes, all hammering being eliminated together with the attendant danger of breaking the glass.

Another object is to provide a glazier's point adapted to frictionally engage the blade of a putty knife and so as to maintain its position thereupon notwithstanding the angular disposition of the knife.

Another object is to provide a glazier's point having a shoulder thereupon so spaced as to automatically indicate to the workman when the point is driven home.

Another object is to provide a form of glazier's point having its rear lateral margins arranged inwardly so as to resist any tendency to work out backwardly through the putty after insertion.

With these and such other objects and advantages as may appear, attention is called to the following specification and to the accompanying drawings as constituting a part thereof, and wherein.

Figure 1 is an elevation of a putty knife having mounted thereupon a glazier's point made in accordance with my invention;

Figure 2 is a view in plan showing the method of cutting the points from sheet metal with very little waste of material;

Figure 3 is a plan view of a point;

Figure 4 is an edge view.

The invention comprises a blank of sheet metal formed to embody a forwardly positioned, tapered entering point 1, laterally aligned stop edges or shoulders 2 back of the entering point and a pair of laterally spaced knife engaging prongs 3, struck up from the blank, one being positioned immediately back of the marginal edge of each stop shoulder at either side of the base line of the entering point 1. The rear edge 4 of the blank is cut off squarely in parallelism with the forward edges of the stop shoulders

2, and the lateral margins 5 are tapered convergingly towards the rear.

In use the point is quickly mounted upon the putty knife 6 by merely slipping the prongs 3 over the front margin of the knife as shown in Figure 1, the prongs being turned forwardly. The point may then be quickly and easily forced into the sash over the glass pane (not shown). The distance between the edges 2 and 4 is slightly less than the width of the putty bead or ledge (not shown) of the sash. The tapering lateral margins 5 act to prevent the retrogressive movement of the point after it is mounted in place and the putty hardens. In Figure 2 is illustrated an economical method of stamping out the points from sheet metal with slight loss of material.

It is thought that the construction and use of the point will be fully understood from the foregoing description.

While I have herein described a certain specific manner and method of constructing and assembling the elements of my invention, it is understood that I may vary from the same in minor details, not departing from the spirit of my invention, so as best to construct a practical device for the purpose intended, as defined in the appended claim.

I claim:

A glazier's point having a forward tapered entering point, laterally aligned stop shoulders immediately back of the entering point, and laterally aligned knife engaging prongs struck up immediately back of the stop shoulders, the rear edge of the point being cut off parallel with the edges of the aligned stop shoulders and the lateral edges being tapered convergingly from front to back.

In testimony whereof I affix my signature.

JOHN I. ROUTLEDGE.
